UNITED STATES PATENT OFFICE

CHARLES W. IRISH, OF KANSAS CITY, MISSOURI

GAS RADIATOR

Application filed May 26, 1928. Serial No. 280,844.

My invention relates to radiators of the class employed for heating dwellings and other structures, and one object is to provide a new and useful radiator which, while of compact form, has the component parts so arranged as to provide maximum radiating surfaces.

A further object is to provide a radiator of symmetrical form and in which the different parts are so arranged that they can be manufactured and assembled at moderate cost.

Another object is to provide a radiator having a central combustion chamber to the opposite sides of which radiator columns are connected in such manner as to insure a rapid circulation of the products of combustion and heated air throughout the length of the combustion chamber and said columns, to the end that great efficiency may be had at a minimum expenditure of fuel.

A further object is to provide a radiator which can be readily enlarged at will to any desired capacity by the addition of radiator columns of like size and construction, so that it will not be necessary to incur the expense of manufacturing the radiators in a large number of different sizes.

Other objects will hereinafter appear and in order that the invention may be fully understood, reference will now be had to the accompanying drawings, in which:

Fig. 1 is a vertical section of the radiator on line 1—1 of Fig. 2.

Fig. 2 is a vertical section of the radiator on line 2—2 of Fig. 1.

Fig. 3 is a horizontal cross section on line 3—3 of Fig. 1.

Fig. 4 is a vertical section of one of a plurality of radiator sections.

Fig. 5 is a detail perspective view of a back plate with a transverse channel and an outlet leading from said channel.

Fig. 6 is a detail perspective view of one of a pair of plates for closing one side of a pair of channels associated with the combustion chamber.

Referring in detail to the different parts, 2 designates a combustion chamber which is approximately of rectangular cross section

and extends, substantially, the entire length of the radiator. The bottom of the combustion chamber 2 has a large opening 4 for the admission of air, while the upper portion of said combustion chamber 2 has two oppositely disposed openings 6 surrounded by flanges 8.

10 designates a pair of channels located at opposite sides of the combustion chamber 2 and extending longitudinally thereof. In order that said channels may be readily formed I provide a pair of plates 12 having flanges 14 at their forward and upper portions which bear against the two adjacent side walls 11 of the combustion chamber 2 and coact with said side walls in forming the channels 10. The rear margins of the plates 12 bear against the rear wall 13 of the combustion chamber 2. The plates 12 are provided with upper and lower studs 16 which coact with the flanges 14 in holding said plates 12 spaced from the side walls 11. Bolts 18 extending through registering holes in the side walls 11 and the plates 12 are provided for firmly holding said plates 12 in place. The side walls 11 have offsets 15 for increasing the width of the channels 10.

20 designates a pair of tubular columns arranged adjacent to the side walls 11 of the combustion chamber 2 and communicating at their upper portions with openings 6 and at their lower portions with openings 22 leading to the lower portions of the channels 10. The columns 20 are provided at their upper portions with flanges 24 which overlap the flanges 8, and at their lower portions with flanges 26 which overlap flanges 28 projecting from the side walls 11 and surrounding the openings 22. Upper and lower bolts 30 and 32, respectively, are employed for securing the combustion chamber 2 and the columns 20 together.

Each column 20 is divided throughout the major portion of its length into a pair of ducts 34 which communicate at their upper and lower portions with each other and the openings 6 and 22. Legs 36 are provided for supporting the columns 20, which in turn support the combustion chamber 2. The upper portions of the columns 20 are provided with

safety valves consisting of plugs 38 which normally close ports 40 in the outer sides of the columns. The plugs 38 are sufficiently loose to be blown from the ports 40 and thus relieve the pressure in the event the fuel in 5 the combustion chamber 2 should explode from being ignited too late.

42 designates a plate for normally closing a large opening 44 in the rear wall 13 of the combustion chamber 2, said plate 42 being held in closed position by suitable means such as bolts 46. The upper portion of the plate 42 has a transverse channel 48 which communicates with the channels 10 and an outlet 50, which latter is formed in the upper portion of the plate 42 and is surrounded by a nipple 52 to which a stove pipe (not shown) may be connected for carrying off the products of combustion to a chimney. The channel 48 is formed by the plate 42 and a C-shaped wall 54, the upper and lower portions of which latter are formed integral with said plate 42. The edges of the C-shaped wall 54 fit into correspondingly shaped flanges 56 formed integral with the adjacent sides of the plates 12, which latter have recesses 58 communicating with the upper portions of the channels 10 and the transverse channel 48.

Any suitable fuel may be used for heating 30 the combustion chamber 2, but in the present instance I have shown a burner 59 which is arranged for the consumption of natural or artificial gas. The burner 59 is of hollow oblong formation and provided at its upper portion with perforations 60 and at its lower portion with an air and gas mixer 62 terminating at its lower end in a downwardly flaring skirt 64. Gas from a suitable source of supply is led through a valve-controlled pipe 40 66 having a jet 68 for discharging the gas into the mixing chamber 62, the discharged gas creating a suction which draws in air through the skirt 64. The air and gas become intimately intermixed in the mixer 62, 45 from which the mixture is discharged against a spreader 70 arranged within the burner 59 for distributing the mixture in an approximately uniform manner to the perforations 60 where the mixture is ignited.

50 The burner 59 is installed in the lower portion of the combustion chamber 2 through the opening 44 in the rear wall 13 and supported at one end by the lower margin of said opening 44 and at its opposite end by an integral lug 72 which rests in the bottom of a recess 74 in a lug 76 formed upon the interior of the front wall 78 of the combustion chamber. The burner 59 is reliably held in place 55 by the plate 42, the lower portion of which is recessed as indicated at 77 to fit over the outwardly projecting end of said burner 59 as shown by Fig. 2. A small opening 80 is provided in the front wall 78 of the combustion 60 chamber to admit a lighted match or wax 65 chamber to admit a lighted match or wax

taper for the purpose of igniting the gaseous mixture when burner 59 is turned on.

With the parts arranged as shown and described it is apparent that when the mixture is ignited at the perforations 60 of the burner 59 the highly heated products of combustion will circulate upwardly through the combustion chamber 2, pass through the openings 6 and down through the ducts 34, thence through the openings 22 into the channels 10, 70 75 through which they flow upwardly and enter the transverse channel 48 from which they escape through the outlet 50, thereby heating all parts of the radiator. The upwardly circulating products of combustion draw in a large volume of fresh air through the opening 4, said air becoming highly heated by the products of combustion and coacting with the latter in filling all portions of the radiator so that the latter will have no cold spots but 80 on the contrary its entire surface will be heated and in turn heat the surrounding air by radiation. If through carelessness the gaseous mixture is not promptly ignited when the burner 59 is turned on and the mixture is 85 permitted to fill more or less of the combustion chamber 2 so that an explosion will occur when a light is finally inserted through the opening 80, the resultant pressure will blow out the plugs 38 of the safety valves and thus 90 95 be relieved to such an extent as to avoid damaging the radiator.

For the purpose of enlarging the radiator whenever desired I provide a number of intermediate columns which are identical to the 100 columns 20, with the exception that the legs 36 and the plugs 38 are omitted and additional openings are formed opposite the openings 22. Any desired number of said intermediate columns can be interposed between the combustion chamber 2 and a pair of the columns 20.

From the foregoing description it is apparent that I have provided a radiator embodying the advantages above pointed out, and while I have shown and described one 110 form of the invention I reserve all rights to such other forms and modifications thereof as properly fall within the spirit and scope of the invention as claimed.

Having thus described my invention, what 115 I claim and desire to secure by Letters Patent, is:

A radiator consisting of a combustion chamber having openings in its upper and lower portions and outwardly projecting offsets in the upper portions of its two side walls, vertically disposed plates removably arranged within the combustion chamber and having marginal flanges registering with said offsets and spacing said plates from the side 120 walls of the combustion chamber to leave vertical channels which communicate at their lower portions with openings in said side walls, means on said plates for cooperating with the marginal flanges in spacing the 125 130

plates from the side walls, means for removably securing said plates to the two side walls, a back plate having an outlet and removably secured to the rear wall of the combustion chamber to close an opening in said rear wall, an approximately C-shaped wall projecting inwardly from said back plate for forming a transverse channel which communicates with the vertical channels and said outlet, the ends of said C-shaped walls fitting into correspondingly shaped supports on the vertically disposed plates, and tubular columns communicating at their upper and lower portions with the openings in the upper and lower portions of the two side walls so that the products of combustion may flow from the combustion chamber down through said tubular columns, up through the vertical channels to the transverse channel and thence escape through the outlet.

20 In testimony whereof I affix my signature.
CHARLES W. IRISH.
